UNITED STATES PATENT OFFICE.

EDWARD A. HANFF, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROLLER.

1,241,510.

Specification of Letters Patent.

Patented Oct. 2, 1917.

Application filed September 10, 1914. Serial No. 860,968.

To all whom it may concern:

Be it known that I, EDWARD A. HANFF, a citizen of the United States, and a resident of Wilkinsburg, in the county of Allegheny and State of Pennsylvania, have invented a new and useful Improvement in Controllers, of which the following is a specification.

My invention relates to controllers, and it has for its object to provide a simple and efficient device for controlling electrical circuits.

The present practice is to employ controllers of the drum type almost exclusively for controlling motors that are employed in connection with planers and similar machines and which are periodically reversed to change the direction of movement of the movable members of the machines.

I provide a controller in which contact members that are biased to a closed position are opened by a cam or other moving element which is connected to the movable member of a mechanically operated switch. My invention is illustrated as employed to control the operation of an electric motor through a series of electromagnetic switches.

In the accompanying drawings, Figure 1 is a view, in elevation, of a controller constructed in accordance with my invention, the front cover being removed. Fig. 2 is a view, in section, of the device of Fig. 1, the cover being in place. Fig. 3 is a diagrammatic view of circuits and apparatus embodying my invention.

Referring particularly to Figs. 1 and 2, a controller 1 comprises a rectangular casing 2 that is provided with lugs 3 by means of which the casing may be secured to any suitable stationary object. A base plate 4 of insulating material is secured to support lugs 5 by means of screws 6. The switching mechanism comprises stationary contact members 7 that are secured to the base plate 4. A corresponding number of movable switch members 8, 9, 10, 11, 12 and 13 are arranged in pairs and are pivotally mounted to coact with the stationary contact members 7. Each of the movable switch members comprises a contact member 14 that is supported by a blade spring 15.

A spring 16, which connects the members of the several pairs of switch elements, tends to separate the switch members and thereby effect the engagement of the coacting contact members. Each of the movable

switch members is provided with a roller 17 to be engaged by a cam member 18. The cam member 18 is provided with projections 19, 20 and 21 which respectively coact with the several pairs of movable switch members. The projections 19 and 20 are of such widths that the switch members 8, 9, 10 and 11 are held in their open positions in the off position of the switch mechanism. The projection 21 is of such width that the switch members 12 and 13, with which it coacts, are in their closed positions when the cam member 18 is in its neutral position. The projection 21 is so arranged that the one or the other of the switch members 12 and 13 is always closed, thereby preventing the opening of the circuit of the shunt field winding. A shaft 22 connects the cam member 18 to an arm 23 which is adapted to be connected to any suitable reciprocating part of a planer or similar machine, the operation of which is to be controlled. The switching mechanism is inclosed by a removable cover 24.

Referring now to Fig. 3, the controller is illustrated as employed in connection with a system of motor control. Line conductors 26 and 27, which may be connected to any suitable source of direct current, supply energy to an electric motor 28 which has a series field winding 29, a shunt field winding 30 and a compensating field winding 31. The system comprises a starting resistor 32 and a field resistor 33 which is provided with movable arms 35 and 36 for including any desired portion of the resistor in circuit. The electrical connections of the arms 35 and 36 are so arranged that one of them is connected in circuit when the motor rotates in one direction and the other is connected in circuit when the motor rotates in the opposite direction. By properly adjusting the movable arms 35 and 36, it will be obvious that different speeds may be automatically obtained for operation in the opposite directions. The circuits of the resistors 32 and 33 are controlled by an electromagnetic switch 37 that is adapted to be actuated in accordance with the counter electromotive force of the motor. The direction of rotation of the motor is controlled by a series of electromagnetic reversing switches 38, 39, 40 and 41. The circuits of the actuating coils of the several reversing switches are controlled by the movable switch mem-

bers 8, 9, 10 and 11 of the controller 1. The movable switch members 12 and 13 of the controller operate to alternately connect the arms 35 and 36 in circuit, according to the direction of rotation of the motor.

5 It may be assumed that the controller arm 23 is connected to a reciprocating member of a planer or other machine (not shown) that is actuated by the motor 28. To start the 10 motor, the main switch 42 is closed to connect the line conductors 26 and 27 to the movable switch members of the controller. It may be assumed further that the controller arm 23, which is illustrated in its off 15 position, has been actuated to the right. 16 In this position of the controller arm, the movable switch members 8, 10 and 12 are maintained in their respective open positions by the corresponding cam members 19, 20 and 21, while the switch members 9, 11 20 and 13 have been permitted to close. The 25 coils of the switches 39 and 41 are energized by a circuit extending from the positive line conductor 27 through the switch 42, conductor 43, switch member 11, coils 44 and 45, conductor 46, switch member 9, conductor 47 and switch 42 to negative line conductor 26. The closing of the switches 39 and 41 completes the motor circuit which 30 extends from the positive line conductor 27 through switch 42, series field winding 29, switch 39, conductor 48, compensating field winding 31, armature winding 28, switch 41, starting resistor 32, conductors 49 and 47 35 and switch 42 to line conductor 26. The switch 37 is normally in its lower position to short circuit the field resistor 33. The motor then rotates in the proper direction to cause the machine to perform, for example, its return stroke. When the motor has 40 been accelerated until its counter electro-motive force reaches a predetermined value, the coil 50 of the switch 37 is energized to actuate the switch 37 to its upper position 45 and thereby shunt the starting resistor 32 and open the shunt circuit for the field resistor 33. The circuit comprising the shunt field winding 30 then extends from the movable switch member 13 which is connected 50 to the positive line conductor 27, through the movable arm 36, a portion of the resistor 33, and shunt field winding 30 to the negative line conductor 26. The motor is further accelerated by the weakened magnetic field caused by the insertion of the 55 resistor 33.

When the reciprocating member of the planer has nearly reached the end of the return stroke, the arm 23 is actuated to the 60 left to reverse the direction of rotation of the motor. In this position of the controller, the movable switch members 9, 11 and 13 are open and the switch members 8, 10 and 12 are closed. The coils 44 and 45 of the 65 switch members 39 and 41, respectively, are

deenergized, while the coils 52 and 53 of the switches 38 and 40 are energized to complete the circuit of the motor for operation in the reverse direction. The operation of the motor for the working stroke is similar 70 to that above described in connection with the return stroke, except that the movable switch member 12 operates to connect the movable arm 35 of the resistor 33 in circuit so that the excitation of the shunt field winding 30 may be varied in accordance with the adjustment of this arm. The operation differs in no other material respect from that described above.

75 A controller constructed in accordance 80 with my invention possesses a number of advantages. The number of units or parts will be materially fewer than in a controller of the ordinary drum type, since a circuit may be completed or broken by a single pair 85 of contacts instead of two contact fingers and a contact segment. The burning of contact fingers may be materially reduced by the use of carbon or graphite contact members, the employment of which is not ordinarily practicable in a controller of the drum type.

85 An important advantage possessed by my invention is that the contact members are actuated to operate with a quick action, 95 which insures that the arcs incident to the closing and opening of electric circuits will be fewer in number and shorter in duration. The multiplying effect caused by the relative lengths of the lever arms of the movable switch members operates to produce a wide and quick separation of the contact members with a comparatively small and slow movement of the operating handle. 100 More accurate stops and reversals are there- 105 by made possible.

I claim as my invention:

1. The combination with a plurality of pairs of movable switch members, of actuating means therefor comprising a member 110 having radially-projecting arms corresponding in number to the pairs of switch members, said switch members and said arms being in substantially the same plane, said arms being movable in opposite directions 115 from neutral positions to control said switches.

2. The combination with a plurality of pairs of coacting stationary and movable contact members mounted in substantially 120 the same plane, of an actuating member between each pair of movable contact members, said actuating member being movable in either direction from an inoperative position to respectively effect the engagement 125 and disengagement of each pair of contact members.

3. The combination with a plurality of pairs of movable switch members, of actuating means therefor comprising a member 130

having a plurality of radially-projecting arms which extend between the members of the respective pairs of switches and are of such widths as to retain certain of said 5 pairs of switch members in an open position and to permit other of said pairs of switch members to be retained in a closed position.

4. The combination with a plurality of pairs of relatively movable contact members, of a cam mechanism for controlling said contact members, said mechanism having an inoperative position in which part of said contact members are in engaged positions and the other of said contact members are in disengaged positions, and having also two operative positions for controlling the positions of said contact members.

5. The combination with an electric motor, and a plurality of switches for controlling the direction of rotation of said motor, of a plurality of movable switch members for controlling the switches, and a cam mechanism for actuating said switch members, said switches and said cam mechanism being mounted in substantially the same plane.

6. The combination with a plurality of movable switch members for controlling electrical circuits, said members being mounted in substantially the same plane, and means for normally retaining said members in one position, of means comprising a cam mechanism movable in the plane of said switch members for actuating said members to a second position.

7. The combination with a plurality of pairs of relative movable switch members, all of which are mounted in substantially the same plane, and means for yieldingly retaining said members in one position, of means for controlling said members, said means comprising an actuating member movable in the plane of said switch members having two operative positions, in one of which, a part of said members is held in a second position, and, in the other of said operative positions, another part of said members is held in a second position.

8. The combination with a plurality of pairs of relatively movable contact members, all of which are mounted in substantially the same plane, and means for yieldingly retaining said members in a closed position, of means comprising a cam mechanism mounted in the same plane with said contact members and movable in said plane for actuating said members, said cam mechanism operating in one position to separate certain of said contact members, and in a second position, to separate certain other contact members.

9. The combination with an electric cir-

cuit and a plurality of pairs of relatively movable contact members for controlling said circuit, of means comprising a cam mechanism for controlling said contacts, said contact members and said cam mechanism being mounted in substantially the same plane, said cam mechanism being movable in said plane and having an inoperative position in which certain of said pairs of contact members are in an open position, said cam mechanism having also two operative positions in which said contact members are alternately actuated to open and closed positions.

10. The combination with an electric circuit comprising a pair of stationary contact members and a pair of coacting movable contact members, of a cam member for actuating said movable contact members, said contact members and said cam member being mounted in substantially the same plane, said cam member being movable in said plane and having an inoperative position in which each of said movable contact members is in an open position and having also two operative positions in which one of said contact members is in an open position.

11. The combination with a plurality of pairs of movable switch members, of actuating means therefor comprising a member having a plurality of radially-projecting arms which extend between the members of the respective pairs of switches and are of such widths as to retain certain of said pairs of switch members in an open position and to permit other of said pairs of switch members to be retained in a closed position, said switch members and said arms being in substantially the same plane.

12. The combination with a plurality of switch members arranged in pairs and movable in the same plane and means for yieldingly retaining said switches in a normal position, of actuating members for the respective pairs of switch members that are simultaneously movable in the same plane.

13. The combination with a plurality of switch members arranged in pairs, the members of said pairs being movable in opposite directions to corresponding positions, and means for yieldingly actuating said members in opposite directions, of means for controlling the switch members, said means comprising a plurality of cams movable in the same plane.

In testimony whereof, I have hereunto subscribed my name this 26th day of Aug. 1914.

EDWARD A. HANFF.
